UNITED STATES PATENT OFFICE.

ANDREW JACKSON, OF WILMETTE, ILLINOIS.

HOISTING APPARATUS.

SPECIFICATION forming part of Letters Patent No. 742,994, dated November 3, 1903.

Application filed July 25, 1903. Serial No. 168,930. (No model.)

To all whom it may concern:

Be it known that I, ANDREW JACKSON, a citizen of the United States, residing at Wilmette, in the county of Cook and State of Illinois, have invented certain new and useful Improvements in Hoisting Apparatus, of which the following is a specification.

My invention relates to improvements in apparatus for hoisting various loads by manual power, and while shown and especially adapted for use in the operation of a traveling hay-fork for unloading hay from a wagon and carrying the same into a haymow it is obviously adapted for use in various other situations.

The object of my invention is to provide a powerful, easily-operated, and portable device for the purposes named. These and such other objects as may hereinafter appear are attained by the devices shown in the accompanying drawings, in which—

Figure 1 is an elevation of my apparatus. Fig. 2 is an end view thereof. Fig. 3 is a like view with the clutch disengaged. Fig. 4 is a side elevation thereof, and Fig. 5 indicates the parts in reversed position.

Like characters of reference indicate the same parts in the several figures of the drawings.

Referring by letter to the accompanying drawings, A indicates a base upon which the apparatus may be mounted, although it may, if desired, be attached directly to the side of a barn or other building. Mounted upon the base A is a pair of brackets B, upon which is mounted a shaft C.

Keyed or otherwise rigidly secured to the shaft C is a ratchet-wheel D, provided with a shoulder d. Loosely mounted on the shaft C is a sleeve carrying a clutch E, a gear-wheel F, and a drum G. Mounted upon the shaft C in such a manner as to normally hold the clutch E on the sleeve in operative engagement with the shoulder d on the ratchet-wheel D is a spring H.

I is a third bracket, between which and one of the brackets B is mounted a shaft J, carrying a spool K, provided with a gear-wheel L. A suitable spring M is provided and so mounted that the rotation of the spool L in one direction will tend to wind up the spring M, so that the tendency of the spring M will

be to rotate the spool L in the opposite direction.

N is a lever so mounted as to be operated by means of a rope O, passing over a pulley P, to throw the clutch E out of engagement with the shoulder d upon the ratchet-wheel D. Q is an operating arm or lever, which may be provided with a rope q, depending from its end. This lever is pivoted at q' and is connected, by means of a link r, with a lever R, which is pivoted at r' and is provided at its opposite end with a weight r².

S T is a compound lever, pivoted at s to the lever R and at t to the base A, the members S T of the lever being pivotally secured to each other at their adjacent ends and being, respectively, loosely pivoted to the lever R and the base A, so as to have some freedom of movement in a direction transversely of the pivots upon which they are mounted. U V X is another compound lever which is slidingly pivoted at s to the lever R by means of a slot (indicated in dotted lines in Fig. 1) and is pivoted at x to the base A and at u to the base A and at both points so as to have some play laterally of the pivots upon which the lever is mounted, the middle member V of this compound lever being pivoted at its opposite ends to the members U and X, respectively. The lever S T is held in its normal position by means of a spring Y interposed between the lever S and the base A and indicated in dotted lines in Fig. 2, while the lever U V X is similarly held in normal position by means of a spring Z, interposed between the members V X and the base A. These compound levers are so mounted that in their normal positions the members T and X, respectively, will be adjacent to and behind successive teeth of the ratchet-wheel D.

The operation of the device as so constructed is as follows: Starting with the apparatus in the position shown in Fig. 1 the lever Q is swung downwardly upon its pivot q and by means of the link r draws the lever R down upon its pivot r', thereby elevating the opposite end of the lever R, carrying the weight r², and at the same time swinging the compound lever S T upwardly. Inasmuch as the member T of the compound lever S T is normally situated adjacent to and just behind one of the teeth of the ratchet-wheel D,

the upward movement of the lever S T upon its pivot *t* causes a pawl-and-ratchet action as between the lever T and the ratchet-wheel D, thereby rotating the ratchet-wheel, while 5 at the same time the ratchet-wheel swings the lever member T inwardly against the tension of the spring Y. At the same time the upward movement of the outer end of the lever R causes a corresponding upward movement of the lower end of the member U of the compound lever U V X upon its pivot *u* and a corresponding downward movement of the members V X of said compound lever to such a position that the spring Z will force 10 the member X outwardly and snugly against the member T of the lever S T, so that the teeth of the ratchet-wheel D, being of sufficient depth, the lever members T and X will simultaneously lie immediately behind and 15 adjacent to the same tooth of the ratchet-wheel D. As the lever Q is now released, the weight r^2 will automatically swing the lever R downwardly, thereby causing a reverse movement of all of the parts, including the elevation 20 of the members Z X of the compound lever U V X, the member X engaging the tooth of the ratchet-wheel behind which it lies and still further rotating the ratchet-wheel as the member X rises, the ratchet-wheel 25 at the same time swinging the member X inwardly against the tension of the spring Z, while at the same time the compound lever S T descends until the member T is behind and adjacent to another tooth of the ratchet-wheel D, whereupon the further 30 downward movement of the lever Q will cause a still further rotation of the ratchet-wheel D, and so on indefinitely, as the lever Q is alternately depressed manually or otherwise 35 and raised automatically by means of the weight r^2 .

It will be seen that by means of the clutch engagement between the sleeve G and the ratchet-wheel D the rotation of the ratchet-wheel D will cause a corresponding rotation 45 of the spool or sleeve G, while by means of the gear-wheels F and M, which intermesh, an opposite rotation of the sleeve K will be caused, while at the same time the spring M 50 is wound up.

Upon the operation of the lever N, by means of the rope O or otherwise, the clutch E is thrown out of engagement with the shoulder *d* upon the ratchet-wheel D, whereupon the 55 tension of the spring M as it unwinds will cause the rotation of the spool K, gear-wheel L, gear-wheel F, and spool G in a direction opposite to that in which they were rotated by the operation of the levers R Q.

60 It will be noted that the gear-wheels F and L are of such relative width that they will not be thrown out of mesh with each other by the disengagement of the clutch E from the shoulder *d*.

65 In the application of my device, for instance, to a hay-carrier the hoisting-rope by means of which the hay-fork is raised to the

usual trolley running on an overhead track and is then drawn along the trolley to a desired point in the haymow is attached to the 70 spool G, so that when the spool G is rotated by the operation of the levers R Q the hoisting-rope will be wound upon the spool G. At the same time the trip-rope is attached to the spool K, is passed through one end of the lever 1, and then behind the pulley 2, and thence to the hay-fork in the usual manner. 75

As the hoisting-rope is wound up upon the spool G the trip-rope is of course unwound from the spool K. 80

The rope O under certain conditions will be passed through the opposite end of the lever 1, so that when the rope O is pulled to shift the clutch E such pull will also take up the slack in the rope O caused by its connection with lever 1, thereby swinging the lever 1 upon its fulcrum and causing a corresponding movement of the opposite end of the lever which engages the trip-rope, thereby pulling the trip-rope and releasing the hay from the 90 hay-fork. 95

As soon as the clutch is disengaged and the hay at the same time released from the fork the unwinding of the spring M will rotate the spool K in a direction to wind up the trip-rope and by means of the coengaging gear-wheels will simultaneously and correspondingly unwind the spool G, and thus unwind the hoisting-rope, whereby the trolley, carrying the hay-fork, is returned to its original 100 position and the hay-fork is allowed to descend to the hay-wagon for another load of hay, and so on. 105

While I have shown a convenient means of constructing my apparatus, I of course do not 110 limit myself to the exact features of construction shown.

I claim—

1. The combination with a ratchet-wheel, of a spool removably engaged thereby, a main 115 operating-lever and a pair of secondary levers arranged to alternately engage teeth upon said ratchet-wheel, so as to rotate the ratchet-wheel and spool, and means for drawing the spool out of engagement with the 120 ratchet-wheel.

2. The combination with a rotatably-mounted ratchet-wheel, of a spool provided with a clutch arranged to engage said ratchet-wheel, a main operating-lever arranged to be 125 manually operated in one direction, means for operating said lever in the opposite direction, and a pair of levers operatively connected with said main operating-lever and arranged to engage the teeth of the ratchet-wheel so as to rotate the ratchet-wheel, and means for throwing the spool out of engagement with the ratchet-wheel at will. 130

3. The combination with a shaft, of a ratchet-wheel mounted thereon, a spool sleeved upon said shaft and having operative connection with said ratchet-wheel, a gear-wheel connected with said spool, a second shaft provided with a spool and with a gear-

wheel meshing with said first-named gear-wheel, a spring adapted to be wound up by the rotation of said second-named spool, a main operating-lever adapted to be operated manually in one direction, means for operating said lever in the opposite direction, and a pair of levers having operative connection with said first-named lever and arranged to alternately engage teeth upon said ratchet-wheel so as to rotate said ratchet-wheel, and means for throwing said first-named spool out of operative connection with said ratchet-wheel, substantially as described.

4. The combination with a shaft, of a ratchet-wheel mounted thereon, a spool mounted upon said shaft and having operative connection with said ratchet-wheel but adapted to rotate independently of said ratchet-wheel, an operating-lever adapted to

be manually operated in one direction, means for operating said lever in the opposite direction, a pair of compound levers arranged to alternately engage the teeth of said ratchet-wheel so as to rotate said ratchet-wheel when actuated by the movement of said first-named lever, and springs arranged to normally throw said compound levers into position to engage the teeth of said ratchet-wheel, substantially as described.

5. An apparatus comprising the brackets B, shaft C, ratchet-wheel D, levers Q, R, S, T, U, V, X, and weight r^2 , substantially as described.

ANDREW JACKSON.
